LAGGING FOR REELS

Arthur A. Bureau, Chicago, Ill., assignor to
 Western Electric Company, Incorporated,
 New York, N. Y., a corporation of New York

Application June 12, 1937, Serial No. 147,915

9 Claims. (Cl. 206—59)

This invention relates to lagging for reels used for storing and transporting heavy material, such as lead covered cable, and more particularly to lagging provided with means for securing the lagging upon such reels.

Although not limited thereto, the present invention is particularly applicable to the securing of a series of sheet metal lags of substantially channel-like cross-section placed side by side across the outer peripheries or rims of metal reel heads to form a complete enclosure for the cable storage space of the reel, and particularly to reels wherein the outer edges of the rims are appreciably inside the end faces of the remaining portion of the reel heads. The rim engaging end portions of the spaced arms of the channel lags are preferably narrowed or reduced in depth by notching the bottom end corners of the arms whereby in addition to appreciably strengthening the lags against impact stresses longitudinal movement of the lags on the reel is effectively prevented. The rim engaging end portions of the lags are reinforced by inserting and welding within each end portion of the lag a filler or liner in the form of a short channel member provided with an outer end wall.

An object of the present invention is the provision of an improved reel lag and simple securing means therefor, whereby lagging may be readily and effectively secured to reels and easily removed therefrom.

In accordance with the above object, the invention contemplates in one embodiment thereof, as applied to reels and lagging of the above mentioned types, lags each having at one end a portion adapted to be hooked over the outer edge of one head rim, the opposite end of the lag having a portion extending over the outer edge of the other head rim and terminating in an outward turned flange. Encircling the lag flanges are a plurality of arcuate lag retaining metal strips, each strip being associated with a predetermined number of lags with opposite ends of the strips bolted to elements fixed to the head behind the ends of the strips.

In accordance with another embodiment of this invention the lags are similar to the lags described hereinbefore except that the portion at one end thereof which terminates in an outward turned flange is formed to terminate in an outward turned hook, the series of hooks being encircled by a lag securing wire rope or band which is first secured at one end to one of a plurality of predeterminedly spaced knobbed studs projecting angularly from the end surface of the reel head

and then entered into a number of the hooks on the lags, comprising a group, and thereafter around another stud and thence over another group of hooks, the rope being applied under tension at each group, and thus continuing around the head until the entire series of lag hooks have been encircled by the rope, and finally securing the free end thereof to the first stud.

Other objects and advantages of this invention will more fully appear from the following detailed description, taken in conjunction with the accompanying drawings, wherein

Fig. 1 is a view in side elevation of a metal cable reel provided with the improved lagging and means for securing the lagging to the reel embodying the invention;

Fig. 2 is an enlarged fragmentary vertical section taken on the line 2—2 of Fig. 1;

Fig. 3 is a fragmentary side view looking at the left end of the structure shown in Fig. 2;

Fig. 4 is a view in side elevation of a metal cable reel showing another embodiment of the means for securing the lagging to the reel embodying the invention;

Fig. 5 is an enlarged fragmentary vertical section taken on the line 5—5 of Fig. 4;

Fig. 6 is a fragmentary side view looking at the left end of the structure shown in Fig. 5;

Fig. 7 is a fragmentary vertical section through a plurality of lags illustrating another embodiment of lagging, and

Fig. 8 is a detail section through one of the knobbed studs of the embodiment shown in Fig. 5.

Referring now to the drawings, a preferred form of lagging embodying the invention is illustrated, for example, in conjunction with a cable reel comprising a pair of spaced heads 10, interconnected by a drum 11 for holding a lead covered cable 12, or other heavy material that may be wound thereon. The cable reel itself may be of any suitable construction, although a welded all-metal construction is preferred. In the construction illustrated, the heads each comprise an inner annular channel member 13, an outer annular rim 14 concentric therewith, channel spokes 15 extending between the inner annular member and the rim and welded thereto, and an annular metallic disc or head sheet 16 welded to the spokes on the side facing the drum.

The spokes are notched at their inner ends, as shown in Fig. 2, to receive the ends of the drum and outwardly turned inner flanges 17 of the head sheets, which, together with the drum, may be welded to the annular channel 13. In the con-

struction illustrated, the spokes 15 are also notched at their outer ends to receive outwardly turned outer flanges 21 of the head sheets, which may be welded to the under side of the rims 14. 5 The outer ends of the channel spokes 15, it will be noted, are narrower than the inner ends thereof and thus the side flanges are inclined inwardly from the annular channel member 13 to the rim 14. This arrangement, wherein the outer edges 10 of the rims are appreciably inside the end faces of the remaining portion of the reel heads, permits the reel to be laid on its end face with the rim and the spokes and the lags, to be presently described, spaced from the ground or other support for the reel.

15 The preferred form of lagging embodying the invention comprises a plurality of lags 25 of uniform size and construction and sufficient in number so that when placed side by side on the 20 rims 14 and lengthwise across the width of the reel, as shown in Figs. 1 and 2, a complete covering or enclosure is provided for the cable storage space of the reel. The lags are preferably of 25 channel-like cross-section and formed from sheet metal. Each lag comprises a substantially flat web portion 26 and integral depending side arms or flanges 27, 27 on opposite sides thereof. As best shown in Fig. 3, the flanges 27 are slightly flared outwardly and at their bottom edges they 30 are formed with outwardly extending open beads to provide rigidity and are slightly resilient to transverse pressure, so that when a series of the lags are laid in place side by side on the rims of a reel and pressed together, the abutted head portions 35 form a tight seal between the lags.

The lags 25 are placed on the reel so that the bottom edges of the flanges 27 thereof contact the rims 14, as shown in Figs. 2 and 3. The rim engaging end portions of the lag flanges 27 are 40 preferably narrowed or reduced in depth by notching the bottom end corners of the flanges, as indicated at 29 (Figs. 2 and 3). The resistance of the lags to impact stresses is thereby increased. Also, the notched corners permit the remaining 45 unnotched portions of the lag flanges to project inwardly between the reel heads and thereby serve as braces therebetween as well as effectively preventing substantial longitudinal movement of the lags on the reel. To further increase the strength of the lags 25 and their resistance to 50 impact stresses the rim engaging end portions of the lags are reinforced by increasing the wall thickness thereof by inserting and welding within the end portions a filler 30 in the form of a short metallic channel member of a cross-section 55 substantially conforming to the cross-section of the notched end portions of the lags. Each reinforcing channel member 30 comprises a web portion 31 and a pair of depending side arms or flanges 32, 32, which at their bottom edges are 60 flush with the bottom edges of the notched end portion of the lag flanges which contact the rims 14. The dimensions are such that the reinforcing channel fits snugly within the notched end portions of the lags, where they may be secured, for 65 example, by spot welding, as indicated at 33 (Fig. 2).

Each of the reinforcing channels 30 is formed with a vertical outer end wall portion 34, preferably formed integral with the web portion 31 and depending therefrom (Figs. 2 and 3). The vertical wall 34 serves as a closure for preventing cinders, stones, etc., from entering the cable storage space of the reel through the otherwise 70 open ends of the lags. In order that the lag

flanges may not be restrained from spreading slightly when under pressure so as to distribute the load over a plurality of lags, the vertical wall portion 34 of the reinforcing channel 30 is preferably not secured to the lag flanges 27 along 5 their adjoining edges. Also, as shown in Figs. 2 and 3, the height of the end wall 34 is slightly less than the flanges 32 of the channel so that sufficient clearance is provided between the rims 14 of the reel heads and the bottom edge of the 10 end wall to permit a free spreading movement of the lag flanges 27.

One embodiment of the improved means for securing the lagging of the above described type to the reel head rims 14 comprises the following. 15 Referring particularly to Figs. 1 to 3, inclusive, the web portion 26 of each of the lags 25 at its left end (Fig. 2) is provided with an integral arm 37 extending inwardly over the end wall 34 of the filler 30 and the outer edge of the associated head rim 14 and terminating in an out-turned flange or lip 38. Encircling the lag lips 38 are a plurality of arcuate shaped lag retaining metal strips 39, which in the present embodiment comprise four strips, each strip retaining a predetermined number of lags on the reel head. Each strip at one end is struck outwardly from the plane of the strip a distance substantially equal to the thickness of the metal, as indicated at 40, and opposite ends of the strips which overlap 30 (Fig. 3) are provided with slots 41. A similar slot is formed in each of the lag arms 37 adjacent the lip 38 thereof. In the present embodiment, four of the spokes 15 of the left reel head (Fig. 2) have welded thereto a plate 45 which spans the 35 inner surfaces of the side flanges of the spoke at their outer edges immediately below the rim 14. The particular spokes which carry the plates 45 are spaced 90° apart corresponding to the points of overlapping of the retaining strips 39. 40 Each of the plates 45 is provided with an aperture for receiving a bolt 47 which in securing the lags to the reel head is passed behind the plate 45 and then through the aperture thereof and the slots of the lag arm 37 and overlapping strips 45 39, respectively.

Each of the lags 25 at their opposite ends is formed with a hook shaped arm 50, which like the arm 37 is formed integral with the web portion 26 and extends inwardly over the end wall 34 of the filler 30 and the outer edge of the associated head rim 14 and terminates in a right angle portion which hooks under the rim as shown in Fig. 2.

To secure the lags 25 to the head rims 14 the reel is preferably mounted on a suitable device 55 whereby it may be freely rotated during the securing of the lags. The first lag 25 is fixed to the pair of head ribs 14 by hooking the arm 50 thereof over the right rim 14 (Fig. 2) and aligning the slot 41 in the arm 37 at the opposite end with the aperture of one of the spoke plates 45 and then inserting the bolt 47 through the aligned aperture and slot. Successive lags 25 are then mounted on the rims 14 side by side to cover one quarter of the rim peripheries and another bolt 47 is then inserted through the aligned aperture of the spoke plate 45 and slot of the lag arm 37, which spoke plate and lag arm are spaced 90° from the first spoke plate, and lag arm, respectively. Thereafter, a retaining strip 39 is mounted in position outside of the series of lag lips 38 with the bolts 47 extending through the slots at opposite ends of the strip.

It will be apparent that the lags 25 between 75

the first and last one of each group, which are bolted to the spokes 15, will be retained in position on the reel heads by the out-turned lips 38 of the arms 37 integral with the lags. The 5 positioning of successive groups of lags 25 and their retaining strips 39 is continued around the heads until the entire rim peripheries have been covered, thereby completely enclosing the cable storage space of the reel. Nuts are then threaded 10 onto the outer ends of the bolts 47 and this completes the effective securing of the lags to the reel. The removal of the lags from the reel it will be obvious may be easily effected.

Referring now to Figs. 5, 6 and 7 which illustrate an alternative embodiment of the improved reel lag and securing means therefor, lags 51 similar to the lags 25, previously described, are employed, except that the arm 37 thereof which terminates in an out-turned lip 38, is formed to 20 terminate in an out-turned hook 52 (Fig. 5). The reel head with which the lag hook 52 is associated is equipped with a plurality of spaced knobbed studs 53 which project angularly from the reel head intermediate the inner channel member 13 and the rim 14. The studs 53 in the particular reel structure illustrated are suitably secured in and welded to the web portions of certain of the spokes 15 spaced, for instance, 45° apart so that a group of lags are positioned on 25 the rim 14 between each pair of studs. Each of the studs inside the head thereof may be provided with a tapered peripheral slot 54 (Fig. 8) in its periphery into which a wire band or rope 55 may be wedged.

To secure the lags 51 to the head rims 14 the reel may be mounted in the manner described in connection with the previously described embodiment and the end of the wire rope 55 is then secured to one of the studs 53 by tying it to and 30 wedging it into the tapered slot thereof. A plurality of lags 51 comprising a group, are mounted side by side on the rims 14, in the manner described hereinbefore, to cover one-eighth of the rim peripheries, the first lag being positioned adjacent the stud to which the end of the wire rope 35 is secured. The wire rope is then entered into the successive hooks 52 of the group of lags, drawn tightly around the following stud and wedged into the slot thereof, and thereafter entered into the hooks of the following group of lags mounted in position, drawn tightly around and wedged into the slot of the next stud and thus continuing around the head, the rope being applied under tension at each group of lags, until 40 the entire series of hooks 52 have been encircled by the single rope, and finally tying the free end thereof to the first stud. The cable storage space of the reel is now completely enclosed by a plurality of groups of lags each group being individually retained in position on the peripheries 45 of the rims 14 in an effective manner. An expeditious removal of the lags from the reel may be effected by merely reversing the above described operations of securing the lags in position.

In Fig. 7 is shown another embodiment of lagging which may be similar to the lagging described hereinbefore, except that the side arms or flanges 27 thereof are designed to interlock as indicated at 60. This is effected by providing 50 one of the flanges 27 at its bottom edge with an open bead 51, which preferably may be less open than the beads indicated on the lagging hereinbefore described, for freely receiving the opposite flange 27 of the adjacent lag which is a plain flange without a bead at its lower edge. To fur-

ther increase the strength of the channel type lags and their resistance to impact stresses, particularly intermediate their reinforced ends, the web portion 26 of the lag may be formed with a longitudinally extending reinforcing embossment or rib 62. Either type of lagging may be used on the reel and either one may be secured thereto by one or the other of the described embodiments of securing means.

The above described types of lagging and the several embodiments of means for securing the lagging upon reel heads permits the lags to be readily and effectively secured to the reel and easily removed therefrom. Furthermore, due to the particular arrangement of the lagging and securing means upon the reel, the reel after being lagged may be laid on either of its end faces or rolled during handling with other reels without damage to the securing means.

Although in the described embodiments of lag securing means the hooked shaped arm 50 is disclosed for securing one end of the lags to the reel rim, it is to be understood that both ends of the lags may be secured in position by being equipped with one or the other of the securing 25 means associated with the other ends of the lags.

It is to be understood that the invention is not limited to the specific embodiments thereof herein illustrated and described except insofar as is defined by the appended claims.

What is claimed is:

1. Lagging for a reel having spaced heads each with a peripheral rim, comprising a series of lags for encircling and spanning the rims, said lags each having portions extending from each end thereof over the outer edge of the rim, the portion at one lag end terminating in an angular arm adapted to hook over the rim, the portion at the opposite end extending outwardly of the rim, and means encircling the series of latter lag portions for securing the lagging upon the reel.

2. Lagging for a reel having spaced heads each with a peripheral rim, comprising a series of lags for encircling and spanning the rims, said lags each having portions extending from each end thereof over the outer edge of the rim, the portion at one lag end terminating in an angular arm adapted to hook over the rim, the portion at the opposite end having a flange extending outwardly of the rim, a plurality of elements, each common to a group of lag flanges, designed to encircle the series of flanges for securing the lagging upon the reel, and means for detachably securing said elements to the reel head.

3. Lagging for a reel having spaced heads each with a peripheral rim, comprising a series of lags for encircling and spanning the rims, said lags each having portions extending from each end thereof over the outer edge of the rim, the portion at one lag end terminating in an angular arm adapted to hook over the rim, the portion at the opposite end having an angularly disposed outwardly extending flange, a plurality of arcuate shaped strips, each common to a group of lag flanges, designed to encircle the series of flanges for securing the lagging upon the reel, said strips overlapping at their opposite ends, and means for detachably securing the overlapping ends of said strips to the reel head.

4. Lagging for a reel having spaced heads each with a peripheral rim, comprising a series of lags for encircling and spanning the rims, means for detachably securing one series of lag ends to one rim, means carried by the opposite end of each

- lag extending over the outer edge of the other rim and provided with a hook portion to receive a flexible tie member, spaced elements disposed upon the reel head inwardly of the rim to which the tie member may be attached, and a flexible tie member applied individually to successive groups of hook means on the lags and between each group thereof being attached to said elements for securing the lagging upon the reel.
5. Lagging for a reel having spaced heads each with a peripheral rim, comprising a series of lags for encircling and spanning the rims, means for detachably securing one end of each lag to one rim, means carried by the opposite end of the lag extending over the outer edge of the other rim and provided with a hook portion to receive a flexible member, a plurality of predeterminedly spaced elements fixed to and projecting outwardly from the end surface of the reel head and arranged inwardly of the rim, and a flexible member secured to one of said elements and engaged with the hook means of a group of lags and around a second element and thence engaged with the hook means of a second group of lags and thus continuing around the head until all of the hook means of the lags have been engaged in groups and the entire series thereof encircled by the member which is applied under tension to each group of hook means and thereafter secured to one of the elements for securing the lagging upon the reel.
6. Lagging for a reel having spaced heads each with a peripheral rim having its outer edge arranged inside the end face of the head, the said lagging comprising a series of lags for encircling and spanning the rims, said lags each having portions extending from each end thereof over the outer edge of the rim, the portion at one lag

end terminating in an angular arm adapted to hook over the rim, the portion at the opposite end extending outwardly of the rim, said opposite end portions of the lags being disposed inside said end faces of the heads, means encircling the series of outwardly extending lag portions and applied individually to successive groups thereof for securing the lagging upon the reel, and means for detachably securing said encircling means to the reel head.

7. Lagging for a reel having spaced heads, comprising a series of sheet metal channel members for encircling and spanning the heads, said members each having a base forming an outer surface and flanges extending toward the interior of the reel, the flanges of each member being designed to interlock with the flanges of the adjacent member.

8. Lagging for a reel having spaced heads, comprising a series of sheet metal channel members for encircling and spanning the heads, said members each having a base forming an outer surface and flanges extending toward the interior of the reel, the longitudinal edge of one flange of each member being turned upwardly to provide a channel for receiving in interlocking relationship the opposite downwardly facing longitudinal edge of the flange of the adjacent member.

9. A reel comprising a drum and spaced heads each with a peripheral rim, a series of lags for enclosing the reel, hooked extensions on each lag end extending over the outer edges of the reel heads, the extensions at one end of the lags adapted to hook over the rim, the extensions at the opposite ends extending outwardly of the rim, and means encircling the series of latter lag extensions for securing the lagging upon the reel.

ARTHUR A. BUREAU.
